ADJUSTABLE BLIND AND CURTAIN SUPPORT

Filed June 25, 1947

UNITED STATES PATENT OFFICE

2,490,890

ADJUSTABLE BLIND AND CURTAIN SUPPORT

Joseph Trimarchi and Lazzaro Pezza,
New York, N. Y.

Application June 25, 1947, Serial No. 756,834

2 Claims. (Cl. 211—103)

1

This invention relates generally to an adjustable blind and curtain support, but more specifically to a type of support for curtains, draperies and Venetian blinds or window shades which may be easily lowered for purposes of repair, adjustment and replacement.

The main object of the invention resides in the provision of a pair of similar movable brackets supported on a pair of bars affixed spacedly to the vertical members of a window frame, each of the said brackets having cooperating means with the bars for maintaining a fixed top operative position thereof and for unlatching from said position for controlled slideable lower position.

Each of the above mentioned movable brackets is provided with means for supporting Venetian blinds, shades, curtains and drapes so that upon release from the top operative position thereof the brackets may be lowered along the bars so that the said window trimmings may be accessible for purposes of repair, replacement and adjustment.

A further object of the invention resides in the provision of movable brackets which are compact, simple in construction, easy to operate and inconspicuous.

These objects and other ends and advantages of the invention will hereinafter appear in the progress of the disclosure and as pointed out in the appended claims.

Accompanying this specification is a drawing showing a preferred form of the invention and wherein:

Figure 1 is a front view in elevation of the brackets in top fixed and operative position and showing the control means therefor.

Figure 2 is a sectional view of Figure 1 across the plane 2—2 thereof.

Figure 3 is a sectional view of Figure 1 across the broken plane 3—3 thereof.

In accordance with the invention and the preferred form shown numeral 10 indicates each one of a pair of bars or rails adapted to be secured to one of a pair of vertical members 11 of the window frame, the said bars each indicated by numeral 10 being shown in the form of an elongated plate member being secured to the vertical members 11 by means of a plurality of spaced screws 12 each penetrating a spacing bushing 13. Each of the brackets is comprised of a vertically disposed plate member 14 having a forwardly extending bracket arm 15 along the outer edge and a rearwardly extending bracket arm 16 along the inner edge. Forwardly extending bracket arm 15 has a tapering lower edge 17 and a straight

2

upper edge 18 disposed above the upper horizontal edge of plate 14. The rearwardly extending bracket arm 16 as shown is narrower in width than forwardly extending arm 15. Plate 14 on the rear face thereof is provided with a pair of vertical angle irons 19 and 20 riveted thereto at attaching flanges as by rivets 21 whereby plate 14 is slidably secured to the bar or plate 10.

At the upper end of each bar 10 is a lateral 10 and inwardly extending arm 22 affixed thereto as by rivets 25, the said arm 22 having a depending spring latch 23 secured thereto as at rivets 24. The lower end of the latch 23 is provided with a hook member 26 adapted to support one 15 of the brackets in uppermost and operative position by engaging the upper edge of an opening 29 in plate 14.

A vertically extending leaf spring 27 secured to the front wall of plate 14 at rivets 28 projects 20 above the upper edge of said plate. The spring latch 23 intermediate the height thereof and the upper edge of leaf spring 27 are adapted to engage respectively a cam 34 and a ratchet wheel 33. Said cam 34 and wheel 33 are mounted in a rear lug 30 on plate 10 on an axle 32 inside a bushing 31, the latter penetrating said lug.

The forwardly extending bracket arm 15 has 30 on the inner face thereof a pair of aligned curtain rod brackets 35 and on the outer face of said bracket arm and spaced thereabove are a pair of drapery rod brackets 36. Adjacent the forward end of the upper edge 18 of the forwardly extending bracket arm 15 is a semi-cylindrical recess 37 which may receive one end of a curtain rod. In addition, adjacent the upper edge 18 there may be a series of openings 38 to retain other window trimmings such as a shade.

Each of the rearwardly extending bracket arms 16 serves to support one end of the supporting head of a Venetian blind and is provided with an adjustable plate 38 secured thereto by means of screw bolts 39 penetrating openings and aligned slots 40 in the bracket arm and plate 38 respectively. Plate 38 on the outer face is provided with a Venetian blind bracket, the bracket having a rearwardly extending horizontal portion 41 terminating at the rear edge in an upright wall 42, and at the forward edge developing into a vertical and depending U-shaped bracket 43. The horizontal wall 41 and the adjacent vertical leg of the U-shaped bracket 43 at the inner edges are provided with attaching flanges 44 and 45 over and through which a plate 46 is riveted to plate 38 as by rivets 47. The U-shaped bracket is adapted to hold a heading

or cross piece while the horizontal portion 41 is adapted to hold one end of the main top cross piece of a Venetian blind.

The means used for raising and lowering both of the brackets 14 comprises a single and double roller 48 and 49 respectively, each of the rollers being secured at the opposing ends of the arms 22. One of the rollers such as 49 has a double groove while the other roller 48 has a single groove. A rope or cord 51 is adapted to be anchored at a forwardly turned flange 50 along the inner end of the upper edge of one of the plates 14 and proceeds over roller 48 and over one of the grooves of roller 49, the other groove of roller 49 being used to receive rope or cord 51a anchored at flange 50 of the other plate 14. The free ends of the cords 51 and 51a are secured together as indicated by the manipulating cord 52.

When manipulating cord 52 is drawn downwardly while the brackets 14 are in uppermost and suspended position at the hooks 26 of latch arms 23, the brackets are raised to the extent of the height of opening 29 and spring arm 27 at the top edge causes a rearward turn of ratchet wheel 33 resulting in movement of cam 34 whereby the latch arm 23 is flexed and disengaged from within the opening 29 permitting the downward movement of the brackets 14 along the rails 10. It is to be noted that the ratchet wheel 33 as shown is provided with six teeth and the movement of a tooth rearwardly displaces axle 32 60°. The 60° displacement causes a corresponding displacement in the triangular cam 34 having flattened corners whereby the latch arm 23 becomes alternately flexed inwardly for disengagement with the window 29 in plate 14 for lowering of the brackets and returned for engagement with the said window when cord 52 is pulled to raise the brackets to operative position. At the initial downward movement of the brackets 14, the spring arm 27 rides over the upper surface of one of the teeth of ratchet wheel 20. When the window trimmings have been applied, manipulated, adjusted or replaced while the brackets are in lowered position, the manipulating cord 52 is pulled and upon engagement between the upper edges of spring arm 27 with one of the teeth in ratchet arms 30 and upon displacement thereof the axle 32 rotates for 60° thereby displacing a corner of cams 34 for releasing the latch arms 23 for engagement with the upper edges of windows 29 for purposes of supporting the brackets in uppermost position.

We wish it understood that minor changes and variations in the integration, the material, location and size of parts of the invention may all be resorted to without departing from the spirit of the invention and the scope of the appended claims.

It is to be noted that the spring latching arm 23 is provided with a central recess 53 which is adapted to engage the corners of the cam 34 when in flexed position to prevent cam rotation. Moreover, when arm 23 is in unflexed condition, spring pressure against the triangular sides of the cam prevents the latter from rotating.

We claim:

1. An adjustable support of the class described, comprising a pair of rails secured to the vertical pieces of a window frame, a pair of brackets each slidably secured to said pair of rails, draw-string means between the brackets and the rails for raising and lowering said brackets, a supporting latch arm secured to the upper end of each rail and engaging an opening in each bracket to support said brackets when in uppermost position, a ratchet wheel secured to each rail adjacent the upper end thereof, a ratchet arm secured to each of said brackets and engageable with each of said ratchet wheels, and cam means operative by said ratchet wheel on each of said rails for releasing the latching arm from each bracket when the brackets are raised above the uppermost supporting position.
2. An adjustable support for window blinds, Venetian blinds, curtains, drapes and the like, comprising a pair of rails secured to the vertical pieces of a window frame, a pair of brackets each slidably secured to one of said rails, draw-string means between said brackets and said rails for raising and lowering said brackets, a common axle rotatably mounted on each rail and having a ratchet wheel and cam secured to opposite ends of said axle, a leaf spring engageable with said axle, a ratchet wheel mounted on each bracket, a latching arm mounted on each rail and engageable with said cam, each bracket having an opening engageable at the upper edge by said latching arm to support each bracket in uppermost and operative position by said leaf spring engaging and rotating said ratchet wheel, whereby said latch arm is moved to engage the upper edge of the opening in the bracket.
